(57) **CLAIM**

The ornamental design for a vegetable spiralizer, as shown and described.

DESCRIPTION

FIG. 1 is a top, front and left side isometric view of a vegetable spiralizer showing my new design;

FIG. 2 is a bottom, rear and left side isometric view thereof;

FIG. 3 is a top plan view thereof;

FIG. 4 is a bottom plan view thereof;

FIG. 5 is a left side elevation view, the left side elevation being a mirror image thereof;

FIG. 6 is a front elevation view thereof;

FIG. 7 is a rear elevation view thereof; and,

FIG. 8 is a cross-sectional view taken in the direction of line 8-8 of FIG. 3.

The broken lines depict portions of the vegetable spiralizer that form no part of the claim.

1 Claim, 5 Drawing Sheets
